PROCESS OF MAKING SIDING ELEMENTS

Clarence R. Eckert, Englewood, N. J., assignor to
The Barrett Company, New York, N. Y., a corporation of New Jersey

Application October 31, 1931, Serial No. 572,325

8 Claims. (Cl. 154—2)

This invention is directed to siding elements, and more particularly, to siding elements of the felt base type, coated with waterproofing material and surfaced with granular material.

5 One object of this invention is to provide a siding element in strip form, durable and resistant to wear and weather, which can be readily applied to walls or other surfaces even by unskilled workmen, and which when applied in 10 overlapping courses simulates the usual brick wall. Another object is to provide an efficient process of producing such siding elements. Other objects and advantages will appear from the following detailed description, taken in connection 15 with the accompanying drawing, in which—

Fig. 1 is a side elevation, somewhat diagrammatic in character and shows the steps involved in the manufacture of the siding element of this invention;

20 Fig. 2 is a fragmentary plan view of the coating, tissue paper applying, and surfacing apparatus, a portion of the sheet being shown in plan for the sake of clearness and to indicate the relative position of the tissue paper covered and surfaced portions of the sheet;

25 Fig. 3 is a front elevation, partly in section, of the tissue paper applying device;

Fig. 4 is a fragmentary plan view of a coated and surfaced base and indicates the layout for 30 cutting the base into individual elements;

Fig. 5 is a plan view of a siding element and illustrates a preferred embodiment of this invention;

Fig. 6 is a vertical section through the siding 35 element of Fig. 5;

Fig. 7 is a fragmentary plan view of a number of overlapping courses, each composed of the siding elements of this invention laid in abutting relationship; and

40 Fig. 8 is a vertical section through a modified form of siding element.

Referring to the drawing, with particular reference to Fig. 1, a sheet of fibrous material 1, which may be, and preferably is, of the usual 45 roofing felt made from rag fiber and paper stock with or without suitable fillers as well known in this art, is fed by feed rolls 2 from the usual paper making machine or felt roll into looping device 3. From the looping device 3, rolls 4 feed the sheet into any customary type of saturating apparatus, indicated generally by the reference numeral 5. Saturating tank 6 may contain suitable cementitious waterproofing composition, such as asphalt or other bituminous material,

utilized for the impregnation and saturation of roofing felts.

Rolls 7 and 8 feed the saturated sheet to a second looping device 9. The passage of the saturated base through the looping device 9 gives the saturant the necessary opportunity to dry and thoroughly impregnate the fibrous base. Rolls 11 and 12 feed the saturated sheet from the looping device 9 to the coating appliances indicated by the reference numeral 13. Rolls 12 5 10 are preferably driven at a slightly greater peripheral speed than that of coating rolls 14, 15, the slack accumulating between driven rolls 12 and guide rolls 16, over which the sheet passes before entering the bite of the coating rolls 14, 15.

15 Coating roll 15 is rotatably mounted in a tank 17. This tank may contain bituminous material such as asphalt or other cementitious waterproofing substances suitable for coating roof-

20 ing felt.

The base of the sheet 1 is completely coated by roll 15. Waterproofing material is applied to the top of the sheet by means of pipe 18 equipped with a discharge spout 19 of a width approximately equal to that of the sheet, as 25 shown in Fig. 2. The coating material is spread uniformly over the top and bottom of the sheet as it passes between the coating rolls 14, 15.

25 Immediately upon leaving the coating appliance and while the coating material is still tacky, 30 the coated sheet passes under the tissue paper, fabric or other paper-applying mechanism 21. As shown in Fig. 3, this mechanism comprises a frame 22 suspended by flexible straps or bands 23 from suitable supports 24. Frame 22 is provided with side extensions 25 arranged to contact with the side edges of sheet 1. Due to the 35 flexibility of the suspending bands 23, the frame moves transversely when the base moves transversely and causes the rolls of tissue paper 26 40 to be constantly maintained in the same relative position with respect to the face of the sheet.

45 Rolls of tissue paper 26 or light weight kraft paper or other paper or fabric of any desired color are rotatably mounted on a shaft 27, carried by frame 22. In the embodiment of the invention disclosed in the drawing, four rolls 26 are shown, the end rolls functioning to apply a band or stripe 28 to the marginal portions of the sheet 1, the outer edge of the tissue paper 50 coinciding with the outer edges of the base 1. The interior rolls are of a width double that of the end rolls and supply tissue paper to form the intermediate parallel, relatively wide, bands or stripes 29. As indicated above, due to the 55

flexible suspension of frame 22, the strips of tissue paper are supplied throughout the longitudinal extent of the base 1, covering substantially parallel longitudinal portions, irrespective of the transverse movement of the sheet. The tissue paper renders the portions of the coated base covered thereby non-cementitious.

Upon leaving the paper applying mechanism, the base passes under hopper 31, containing granular material, such as crushed rock or slate. Preferably, red colored granules are deposited in this hopper. These granules are showered, by means of the usual distributing roll 32, onto the base therebeneath and adhere to the longitudinal, cementitious striped portions 33, occurring between the tissue paper covered portions. The thus surfaced sheet then passes about reversing roll 34, which functions to partially embed the granular material in the plastic coating. The tissue paper covered portions being noncementitious, granules do not adhere thereto and upon the sheet leaving roller 34, the granules resting on the tissue paper covered portions and the excess granules on the granular embedded portions fall off therefrom into hopper 31, from whence they were delivered onto the base 1.

In the continued passage of the surfaced sheet, it comes under the hopper 35. Mica dust, talc, or other composition capable of rendering the back of the sheet non-cementitious is deposited in hopper 35 and discharged therefrom by distributing roll 36. The talc covered sheet then passes over reversing roll 37, which imparts a smooth surface to the back of the sheet. Excess talc falls off from the base as the latter passes from roll 37 to the drying and pressing rolls 38. Hopper 35 is preferably so positioned that the excess talc falls back thereinto, as shown in Fig. 1.

Feed rolls 41 feed the sheet from the pressing rolls 38 into a looping device 42, where the product is given an opportunity to cool. From the looping rack 42, the surfaced sheet passes through rolls 43 to the cutting cylinders 44. These cylinders simultaneously cut rows of slots 45 in the granular surfaced portions of the sheet. The individual slots 46 of each row are of a length preferably equal to the width of the granular surfaced portions 33. The sheet is simultaneously cut longitudinally along longitudinal lines 47 intersecting the slots 46 midway between the ends thereof and also along lines 48 coinciding with the median line of the wide tissue paper covered portions 29. Simultaneously with the longitudinal cutting operations, the base is cut transversely along lines indicated by the reference numeral 51.

The transverse cuts 51 are spaced apart a distance corresponding to the length of the desired element and are shaped as shown in Fig. 4 so that one transverse edge of each element is formed with a triangular projection while the other transverse edge is provided with a complementary recess. Preferably the slotting and the longitudinal and transverse cutting operations are accomplished by passing the surfaced base through cutting rolls which substantially simultaneously make all the cuts, but they may be formed in any desired order, the slotting operation preceding or following the cutting of the base into longitudinal strips. From the cutting rolls 44, the cut sheet passes through tab knocker and ejector cylinders 52 of any well known type which remove portions of the material cut out to form slots and adhere to the cut sheets. From the tab ejector mechanism, the individual elements pass to suit-

able stacking appliances 71, indicated diagrammatically on Fig. 1 of the drawing.

The siding element resulting from the above described operations is shown on Figs. 5 and 6. It consists of a felt base 55 having coatings 56 of bituminous or other waterproofing composition on both sides thereof. Tissue paper 57 covers the top coating 56, the tissue paper extending from the upper longitudinal edge of the element down to the upper edge of the slots between the rectangular tabs disposed along one longitudinal edge of the siding element. The tabs have granular material 58 partially embedded therein. Due to the fact that the layer of granular material 58 is substantially thicker than the thickness of the tissue paper, the forward exposed portion of the element is of greater thickness than the upper unexposed portion. Mica dust or talc layer 59 covers the rear surface of the element. Side edge 61 is formed with a triangular projection 62 and the other side edge 63 has a complementary recess 64.

The element of Figs. 5 and 6 is designed to be laid in overlapping courses with the triangular projection 62 snugly fitting within the recess 64 of a contiguous element in the same course as shown in the top course of Fig. 7. Hence, the triangular projection and complementary recess aid in aligning the elements in each course. The forward edges of the elements of one course are laid so that they occur above the upper edge of the slots of the elements of an underlying course. Application of the siding elements in this manner results in black (the color of the tissue paper covered portions) longitudinal slots 66 and black transverse slots 67 contrasting with the red or brick color of the surfaced tabs. As appears from Fig. 7, the resultant arrangement of the elements resembles a brick wall.

The siding element of Fig. 8 has the body portion thereof completely covered with fine granular material 72, partially embedded in the coating layer 57. One example of the mesh characteristics of a fine granular material suitable for surfacing the body portion is as follows:

	Per cent
Retained on a 28 mesh screen	0 to 5
Retained on a 35 mesh screen	20 to 40
Retained on a 48 mesh screen	30 to 50
Retained on a 60 mesh screen	15 to 25
Retained on a 100 mesh screen	3 to 8
Passing through 100 mesh screen	0 to 2

The granular material 58, which may be crushed rock, slate, or other grit employed for surfacing roofings, on the tabs of the elements of Fig. 8 is much coarser than the fine granules 72. As one example of the mesh characteristics of the coarse granular material 58 suitable for covering the tab portions, the following is given:

	Per cent
Retained on the 6 mesh screen	0
Retained on the 8 mesh screen	approximately 19
Retained on the 10 mesh screen	approximately 67
Retained on the 14 mesh screen	approximately 12
Retained on the 20 mesh screen	approximately 1.5
Retained on the 28 mesh screen	approximately 0.5

It will be noted that the major portion of granules 58 covering the tabs is retained on a 10 mesh screen whereas the major portion of the fine granules 72 covering the body portion of the element passes through a 35 mesh screen. The use of granular material of such extremes in mesh characteristics for surfacing the body portion and the tabs of the elements results in the tab portions having the appearance of substan-

tially greater thickness than the body portion. The elements of Fig. 8 are laid in overlapping relation in courses in much the same manner as illustrated in Fig. 7 in connection with the siding elements of Fig. 5. Thus a narrow strip of fine granular material corresponding to the exposed portion, represented by the reference numeral 66, is exposed between adjacent courses of elements. The fine granular material thus exposed and that exposed through the slots separating the tabs of the elements contrasts with the coarse granular material of the tabs. Utilizing blue-black fine granules and red or other brick colored coarse granules for surfacing the body portion and tab portions of the elements, respectively, the application of the elements in overlapping courses results in the fine granular portions surrounding each tab simulating mortar disposed about the brick appearing tab portions. In other words, the elements, when laid in overlapping courses impart to the observer the appearance of a brick wall, the mortar simulating portions appearing to be depressed about the confines of the brick portions, as in actual brick wall construction.

In fabricating the elements of Fig. 8, apparatus such as shown in Fig. 1 may be utilized except that hopper 31 is provided with six partitions to divide it into seven compartments, each of a width corresponding with the width of a band or stripe of granular material applied to the coated felt base. Coarse and fine granules are placed in alternate compartments so that when the coated sheet passes thereunder, the coarse granules cover the stripes or bands represented by the reference numeral 33 and the fine granules cover the areas designated by the reference numerals 28, 29. The thus surfaced fabric is then treated as described in connection with the siding element of Fig. 5 to form the desired end product depicted in Fig. 8.

It will be noted that the siding element of this invention involves substantially no waste in its manufacture; can be readily applied even by unskilled workmen; and when applied in the intended manner simulates a brick wall. The tissue paper covers the major portion of the element and since tissue paper costs less than the granular surfacing material, the elements of this invention are more economical to manufacture than the usual granular surfaced shingle element, and this without interfering with the weathering properties thereof. The asphalt or other bituminous coating composition covered by the tissue paper efficiently protects the felt base from weathering influences. Further, owing to the tissue paper covering and granular surfacing, the siding elements may be readily packed and unpacked without danger of one element adhering to another in the package.

Since certain changes in carrying out the above process, and certain modifications in the article which embody the invention may be made without departing from its scope, it is intended that all matter contained in the above description or shown in the accompanying drawing shall be interpreted as illustrative and not in a limiting sense.

I claim:

1. The process of making siding elements, which comprises completely coating one face of a felt base with cementitious waterproofing material, applying narrow strips of tissue paper to spaced longitudinal areas of said coated base, surfacing the remaining areas of said coated base with granular material, and cutting said base

longitudinally and transversely into siding elements.

2. The process of making siding elements having rectangular tabs along one longitudinal edge thereof, which comprises completely coating a 5 felt base with bituminous material, applying strips of tissue paper to spaced longitudinal, substantially parallel, areas of said coated base, partially embedding granular material in the coated areas not covered by said tissue paper, cutting 10 rows of spaced slots through said granular surfaced longitudinal areas, and cutting transversely through the tissue paper covered longitudinal areas and longitudinally along lines intersecting the rows of slots to form said elements. 15

3. The process of making siding elements, which comprises completely coating one face of a felt base with cementitious waterproofing material, applying narrow sheets of non-cementitious material to spaced longitudinal areas of said 20 coated base thereby leaving uncovered spaced cementitious areas of said coating material, said spaced uncovered cementitious areas being continuous in a direction longitudinally of the sheet, surfacing said continuous cementitious areas with 25 granular material, and cutting said base longitudinally and transversely into siding elements.

4. The process of making siding elements having rectangular tabs along one longitudinal edge thereof, which comprises completely coating one 30 face of the saturated felt base with bituminous material, continuously applying strips of tissue paper to the longitudinal marginal portions of the felt base, with one edge of the tissue paper substantially coinciding with the side edges of 35 the felt base, and simultaneously applying parallel strips of tissue paper to the intermediate portion of the base, the intermediate strips of tissue paper being of width substantially double that of the marginal strips and being spaced 40 apart and substantially parallel to each other, partially embedding granular material in the longitudinal portions not covered by said tissue paper, cutting rows of slots through the portions having the granular material thereon, said slots 45 being of a length approximately equal to the width of the granular surfaced portion, cutting the base longitudinally substantially midway between the intermediate tissue paper covered portions, and also midway between the slots 50 of each row, and also transversely through the tissue paper covered portions, the transverse cuts being spaced apart a distance corresponding to the length of the individual siding element.

5. The process of making siding elements which 55 comprises completely coating one face of a felt base with a layer of cementitious waterproofing material of uniform thickness, partially embedding fine granular material in spaced longitudinal substantially parallel areas of said coating, 60 surfacing the remaining areas of said coated base with coarse granular material, and cutting said base longitudinally and transversely into siding elements.

6. The process of making siding elements having rectangular tabs along one longitudinal edge of the body portion thereof, which comprises completely coating a felt base with bituminous material, applying strips of tissue paper to spaced longitudinal substantially parallel areas of said 70 coated base, each strip of tissue paper being of a width equal to at least the width of the body portion of the siding element and contiguous strips being spaced apart a distance equal to at least the depth of the tabs, partially embedding 75

granular material in the coated areas not covered by said tissue paper, cutting rows of spaced slots through said granular surfaced areas, and cutting the resultant felt base longitudinally and transversely to form said elements.

7. The process of making siding elements having rectangular tabs along one longitudinal edge of the body portion thereof, which comprises completely coating a felt base with waterproofing material, rendering selected spaced independent substantially parallel longitudinal areas non-cementitious, partially embedding granular material in the remaining areas of said base, cutting longitudinal rows of spaced slots in the granular surfaced areas of said base, each slot in each row being of a length approximately equal to the width of the granular-surfaced portion in which the row of slots is cut, cutting the base longitudinally substantially midway between

the slots of each row and also midway between the said non-cementitious areas and transversely of said granular surfaced areas and said non-cementitious areas to form said siding elements.

8. The process of making siding elements, which comprises completely coating one face of a fibrous sheet with cementitious waterproofing material, rendering selected spaced, independent, longitudinal, substantially parallel areas non-cementitious thereby leaving spaced, substantially parallel, continuous longitudinal areas of said sheet cementitious, partially embedding granular material in said continuous cementitious areas and cutting said sheet longitudinally intermediate the boundary edges of said non-cementitious areas and said granular surfaced areas and transversely to form siding elements.

CLARENCE R. ECKERT.
